(57) **CLAIM**

The ornamental design for an ice skate blade holder as shown and described.

DESCRIPTION

FIG. 1 is a front top right view perspective view of the ice skate blade holder;

FIG. 2 is a front top left perspective view thereof;

FIG. 3 is a right side view thereof;

FIG. 4 is a left side view thereof;

FIG. 5 is a back view thereof;

FIG. 6 is a front view thereof; and,

FIG. 7 is a bottom view thereof.

The broken lines disclosed on the drawings form no part of the claimed design.
